By their Attorney Arthur R. Foerster,
Edgar Gates

UNITED STATES PATENT OFFICE.

SAMUEL COHEN AND ARTHUR R. FOERSTER, OF NEW YORK, N. Y.

BUTTON DEVICE.

1,356,906.

Specification of Letters Patent. Patented Oct. 26, 1920.

Application filed June 17, 1920. Serial No. 389,550.

To all whom it may concern:

Be it known that we, SAMUEL COHEN and ARTHUR R. FOERSTER, citizens of the United States, and residing at New York, in the county of New York and State of New York, have invented certain new and useful Improvements in Button Devices, of which the following is a specification, such as will enable those skilled in the art to which it appertains to make and use the same.

This invention relates to button devices and particularly to what are known as collar buttons, and the object of the invention is to provide a button of the class specified with a movable resilient and padded back member which is designed to prevent the discoloring or poisoning of the neck of the wearer as well as to prevent binding and pinching of the neck of the wearer in the use of the collar button; and with this and other objects in view the invention consists in a device of the class and for the purpose specified, constructed and operating as hereinafter described and claimed.

The invention described and claimed herein is an improvement on that shown, described and claimed in a prior application filed by us August 27, 1919, Serial No. 320,114, and is fully disclosed in the following specification, of which the accompanying drawing forms a part, in which the separate parts of our improvement are designated by suitable reference characters, in each of the views, and in which:

Figure 1 is side view of a collar button made according to our invention and showing the same on an enlarged scale; and,

Fig. 2 is a central transverse section, through the button shown in Fig. 1.

In practice, we provide an improved button member 5 which is of the usual or any desired form and construction and preferably composed of sheet metal fashioned to form a head 6, a reduced neck portion 7 and an enlarged hollow base portion 8.

A supplemental button member 9 is loosely mounted in connection with the base portion of the main button member 5 and comprises a disk 10 having an upwardly directed sleeve portion 11, the edge portion of which is flared outwardly as shown at 12, after a closure disk 13 has been placed on the sleeve 11 to retain said closure disk in connection with the disk 10.

In constructing the complete supplemental button member 9 a ring member 14,

preferably U-shaped in form in cross section, is mounted around the periphery of the disk 10 to retain a pad member 15, preferably composed of sponge rubber in connection with the disk 10 and also to seal the edge portion 16 of a fibrous covering sheet 17 in position, the covering sheet 17 being passed over and adapted to inclose the cushion member 15, as clearly illustrated in Fig. 2.

In forming the complete button device, the main button member 5 is first made into the desired form, after which the supplemental button member is formed by providing the disk 10 and securing the closure disk 13 thereto by the flare 12 on the sleeve portion 11 and in such manner as to permit of a rotatable and lateral movement of the disk 10 and sleeve 11 on the closure disk 13. The closure disk 13 is secured to the base portion 8 of the main button member by spinning or otherwise fashioning the periphery of said closure disk over the periphery of the base portion 8, as shown at 18, and said disk 13 forms a closure for the bottom of the main button member and also serves to retain the supplemental button member in connection with the main button member. A spiral spring 19 is placed with in the main button member before the closure disk 13 is secured in position. This spring normally serves to hold the supplemental button member in an extended position and provides for a resilient action of the supplemental button member in connection with the main button member, in the inward and outward movement of the same.

By securing the pad member 15 to the disk 10 by means of the ring member 14, the flexible area of said cushion member is increased thus increasing the cushioning qualities of the button device.

We have found through experiences that by providing the independent closure disk 13 for the main button member 5 and securing the same to the base portion of said button, for the purpose of attaching the supplemental button member to the main button member, the production of the device is materially simplified as well as a great saving in the cost of production effected. The fibrous covering sheet 17 is preferably composed of a waterproof fabric which may be washed or cleaned, whenever necessary or desirable. While we have shown certain details of construction for carrying our inven-

tion into effect, it will be apparent that we are not necessarily limited to these details, and various changes therein and modifications thereof may be made, within the scope 5 of the appended claims, without departing from the spirit of our invention or sacrificing its advantages.

Having full described our invention, what we claim as new and desire to secure by 10 Letters Patent, is:—

1. A device of the class described comprising a main button member consisting of a head, a shank and a hollow base, a supplemental button member, and means 15 secured to the base of the main button member for loosely and permanently mounting said supplemental button member in connection with the main button member.

2. A device of the class described comprising a main button member consisting of a head, a shank and a hollow base, a supplemental button member, means secured to the base of the main button member for loosely and permanently mounting said supplemental button member in connection with the main button member, and the outer face 25 of the supplemental button member being provided with a fibrous covering.

3. A device of the class described comprising a main button member consisting of a head, a shank and a hollow base, a supplemental button member, means secured to the base of the main button member for loosely and permanently mounting said supplemental button member in connection with the main button member, and the outer face 35 of the supplemental button member being provided with a fibrous covering between which and the face of said supplemental button member is a suitable padding.

4. A device of the class described comprising a main button member, a closure disk secured to the base portion of said button member, and a supplemental button member loosely mounted in connection with 45 said closure disk and retained against displacement therefrom, said supplemental button member being provided with a fibrous covering.

5. A device of the class described comprising a main button member, a closure disk secured to the base portion of said but-

ton member, a supplemental button member loosely mounted in connection with said closure disk and retained against displacement therefrom, and comprising a disk on the outer face of which is mounted a suitable padding outwardly of which is a fibrous covering, and an annular member mounted on the periphery of said disk for securing said padding and the edge portions of said fibrous covering in connection with said disk. 55

6. A device of the class described comprising a main button member, a closure disk secured to the base portion of said button member, a supplemental button member loosely mounted in connection with said closure disk and retained against displacement therefrom, and comprising a disk on 60 the outer face of which is mounted a suitable padding outwardly of which is a fibrous covering, an annular member mounted on the periphery of said disk for securing said padding and the edge portions of said fibrous covering in connection with said disk, and a spring mounted within the main button member and in connection with which the supplemental button member operates. 70

7. A device of the class described comprising a main button member and a supplemental button member, and means secured to the base portion of the main button member and on said supplemental button member loosely mounting said supplemental button member in connection with the main button member. 80

8. A device of the class described comprising a main button member, a closure disk secured to the base portion of said button member, and a supplemental button member loosely mounted in connection with 85 said closure disk and retained against displacement therefrom.

In testimony that we claim the foregoing 95 as our invention we have signed our names in presence of the subscribing witnesses this 14th day of June, 1920.

SAMUEL COHEN.
ARTHUR R. FOERSTER.
